(57) **CLAIM**

The ornamental design for a drywall sheet with grooves for folding, as shown and described.

DESCRIPTION

FIG. 1 is a front, top and right side perspective view of a drywall sheet with grooves for folding according to our new design;

FIG. 2 is a front, bottom and right side perspective view thereof;

FIG. 3 is a right side elevational view thereof;

FIG. 4 is a front elevational view thereof;

FIG. 5 is a left side elevational view thereof;

FIG. 6 is a rear elevational view thereof;

FIG. 7 is a top plan view thereof;

FIG. 8 is a bottom plan view thereof;

FIG. 9 is an enlarged view of detail FIG. 9 shown in FIG. 1; and

FIG. 10 is an enlarged view of detail FIG. 10 shown in FIG. 3.

FIG. 11 is a front, bottom and left side perspective view of the drywall sheet with grooves of FIGS. 1 to 10 with a rear portion of the drywall sheet folded along a groove, a bottom of the rear portion meeting a bottom of a front portion of the drywall sheet;

FIG. 12 is a rear, top, and left side perspective view thereof;

FIG. 13 is a left side elevational view thereof;

FIG. 14 is a rear elevational view thereof;

FIG. 15 is a right side elevational view thereof;

FIG. 16 is a front elevational view thereof;

FIG. 17 is a bottom plan view thereof;

FIG. 18 is a top plan view thereof;

FIG. 19 is an enlarged view of detail FIG. 19 shown in FIG. 11; and

FIG. 20 is an enlarged view of detail FIG. 20 shown in FIG. 13.

FIG. 21 is a front, bottom and left side perspective view of the folded drywall sheet with grooves of FIGS. 11 to 20 on a stack of folded drywall sheets with grooves.

FIG. 22 is a front, top, and right side perspective view of a the drywall sheet with grooves of FIGS. 1 to 10 folded along two grooves and wrapping an end wall; and

FIG. 23 is a top plan view thereof.

FIG. 24 is a front, top and right side perspective view of another modified drywall sheet with grooves for folding according to our new design;

(Continued)

FIG. 25 is a front, bottom and right side perspective view thereof;

(56)

FIG. 26 is a right side elevational view thereof;

FIG. 27 is a front elevational view thereof;

FIG. 28 is a left side elevational view thereof;

FIG. 29 is a rear elevational view thereof;

FIG. 30 is a top plan view thereof; and

FIG. 31 is a bottom plan view thereof.

FIG. 32 is a front, top, and right side perspective view of a modified drywall sheet with grooves of FIGS. 24 to 32 folded along two grooves and wrapping an end wall; and, FIG. 33 is a top plan view thereof.

The broken lines, the break lines, and the appearance of any portion of the article between the break lines represent unclaimed environment only and form no part of the claimed design.

1 Claim, 22 Drawing Sheets
